US0D1078690S

(12) **United States Design Patent** (10) Patent No.: **US D1,078,690 S**
(45) Date of Patent: ** Jun. 10, 2025

(54) **AUDIO DEVICE**

(71) Applicant: **Inova Design Solutions Ltd**, London (GB)

(72) Inventors: **Leon Marsh**, London (GB); **Cianan O'Dowd**, London (GB); **Emily McLoughlin**, Cambridge (GB); **Matthew Clements**, London (GB)

(**) Term: **15 Years**

(21) Appl. No.: **29/898,341**

(22) Filed: **Jul. 26, 2023**
